UNITED STATES PATENT OFFICE.

MARIANO BERTODO AND ROBERT F. MOHR, OF NEW YORK, N. Y.

SCAFFOLD.

1,092,422.

Specification of Letters Patent.

Patented Apr. 7, 1914.

Application filed April 15, 1913. Serial No. 761,172.

To all whom it may concern:

Be it known that we, MARIANO BERTODO and ROBERT F. MOHR, citizens, respectively, of Italy and the United States, and residing at 5 New York, in the county of New York and State of New York, have invented certain new and useful Improvements in Scaffolds, of which the following is a specification, such as will enable those skilled in the art to 10 which it appertains to make and use the same.

This invention relates to scaffolds and scaffold supports, and particularly to devices of this class used in connection with 15 high buildings employing a steel or iron frame in connection with which walls of brick or brick and stone are built after the framework has been completed, and the object thereof is to provide improved means for 20 raising the scaffold as the building of the wall or walls progresses; and with this and other objects in view the invention consists in a device or apparatus of the class specified constructed as hereinafter described and 25 claimed.

The invention is fully disclosed in the following specification of which the accompanying drawing forms a part, in which the 30 separate parts of our invention are designated by suitable reference characters in each of the views, and in which:—

Figure 1 is an outside or front view of a scaffold made and supported according to our invention; Fig. 2 a transverse section on 35 the line 2—2 of Fig. 3; Fig. 3 a view similar to Fig. 1, but showing only one end portion of the scaffold and showing the same on an enlarged scale, and; Fig. 4 a section on the line 4—4 of Fig. 3.

In Fig. 1 of the accompanying drawing 40 we have shown at *a* some of the upright beams or columns of the steel frame of a building, at *a*² the horizontal beam or beams of a floor and ceiling construction at the top 45 of one of the stories of the building, and at *a*³ a part of one of the brick walls under process of construction. We have also shown in Fig. 1 a scaffold which consists, in the construction shown, of two support 50 members *c* connected by horizontal boards *d* and suspended by cables *e*, as hereinafter described.

The supporting members *c* involve, in 55 their construction, a main framework *c*² comprising two parallel side plates *c*³ connected at the top and bottom by rods *c*⁴ and

*c*⁵ on which are mounted sleeves *c*⁶ and *c*⁷ provided, in the form of construction shown, with grooved wheels *c*⁸ and *c*⁹ loosely mounted thereon, and said supports are also provided at the bottom thereof with pivoted supplemental frame members *f* comprising side plates *f*² mounted on the ends of the rods *c*⁵ and the free end portions of which are connected by transverse rods *f*³ provided with sleeves *f*⁴ on which are loosely mounted grooved wheels *f*⁵, and in the form of construction shown, the free end portions of the side plates *f*² of the supplemental frames *f* are curved inwardly, as shown at 60 *f*⁶, and said supplemental frames are thus made yoke-shaped in form and the free end portions thereof made narrower than the end portions thereof that are pivoted at the bottom of the main frames, but this narrowing of the free end portions of the supplemental frames *f* is not essential. The main frames of the supports *c* are also provided with transversely arranged drums *g* and *h*, and the cables *e* are connected with and 65 wound on the drums *g* which are mounted over the drums *h*, and other cables *i* are connected with and wound on the drums *h*. 70

The outer sides of the main frames of the supports *c* are provided centrally thereof 75 with brackets *j* in which are mounted horizontal shafts *k* provided centrally with worms *k*², and on the inner sides of said brackets and inwardly of the main frames of said supports are mounted vertical shafts *m* provided centrally with gears *m*² which mesh with the worms *k*² and operate through slots or openings *j*² in the brackets *j*, and the shafts *m* are provided with top and bottom supports *m*³ and *m*⁴ and the brackets *j* are provided 80 with ears *j*³ through which the shafts *m* pass. The shafts *m* are also provided with worms *n* and *n*² which mesh with large gears *n*³ and *n*⁴ on the corresponding ends of the drums *g* and *h*, and the opposite ends of said 85 drums are provided respectively with ratchets *g*² and *h*², and supported over the ends of the drums *g* and *h* with which the ratchets *g*² and *h*² are connected are dogs *g*³ and *h*³ which operate in connection with the 90 ratchets *g*² and *h*². The dogs *g*³ and *h*³ are mounted on pins *g*⁴ and *h*⁴ secured in the corresponding sides of the main frames of the supports *c*, and the drums *g* and *h* are provided with axles or shafts *g*⁵ and *h*⁵ rotatably mounted in the opposite sides of said 95 frames. 100

Mounted loosely on the shaft m between the gears n and n^2 and the bracket j are sleeves o and o^2 , and the sleeve o rests normally on the bracket j or the top ear j^3 thereof, while the sleeve o^2 rests on the worm n^2 and the worm n is provided at its upper end with a hub n^5 through which is passed a screw, pin or bolt p by which said gear is secured to said shaft, and the worm n^2 is provided at its lower end with a hub n^6 through which is passed a screw, pin or bolt p^2 and by means of which said gear is secured to said shaft. The shafts k are provided with cranks r , and by turning said shafts by means of said cranks, the scaffold may be raised or lowered in the usual manner and as will be readily understood.

In using scaffolds of this class in connection with building constructions, it is customary to employ beams or bars s which are placed on the floor and ceiling construction beams a^2 and are secured thereto and which project forwardly, or beyond the wall of the building, and in practice, the cables e are provided with clamps or hangers e^2 adapted to be connected with said beams or bars and by which the scaffold is supported, and with our construction, the cables i are passed downwardly and around the wheel c^9 in the base of the main frames of the supports c , and then around the wheel f^5 in the free ends of the supplemental frames f , and then carried upwardly and connected with the beams or bars s in the same manner as the cables e , and the scaffold boards d are laid on the supplemental frames f which are supported in a horizontal position by the cables i , and the free end portions of which extend backwardly from the main frames or supports c^2 and may abut against the wall a^3 as the building of said wall progresses.

Although we have shown and described a scaffold provided with two of the supports c only, it will be understood that the number of these devices will depend on the length of the scaffold, and 3, 4 or 5, such supports may be employed if desired, and each of said devices may be operated by means of the crank shafts k to raise the scaffold, and it will be observed that the shafts k and cranks r extend transversely of the scaffold or scaffold boards d , and this facilitates the operation of said shafts k in raising and lowering the scaffold.

In operating scaffolds of this class, it is customary, when the wall which is being built reaches a certain height, to elevate the supporting beams or bars s and suspend the scaffold from a higher support. With our improvement this operation may be performed by providing other supporting beams or bars and placing them at a higher point than those first employed, and connecting therewith supplemental or independent

cables which are secured to the top cross bar 65 members c^4-c^8 of the main frames c^2 of the supporting members c , after which the worms n and n^2 on the shafts m may be loosened and the gear n raised and the gear n^2 lowered so as to throw said gears out of 70 engagement with the corresponding drum gears n^3 and n^4 after which the dogs g^3 and h^3 may be turned out of engagement with their corresponding drum ratchets g^2 and h^2 , after which the cables e may be detached 75 from the supporting beams or bars s with which they were first connected, and raised and connected with the supplemental beams supported at a higher point, in which operation the drum gears n^3 and n^4 will turn 80 freely; and at the end of this operation the worms n may be again lowered and the worms n^2 raised so that said gears will engage the corresponding drum gears n^3 and n^4 , and the scaffold will be again ready for 85 use and the building of the wall may be proceeded with. If, at any time, during the operation or use of the scaffold, the dogs g^3 and h^3 should be broken or be accidentally thrown out of operation or fail to operate, 90 the worms n and n^2 meshing with the gears n^3 and n^4 would prevent the scaffold from falling, unless said worms n and n^2 were torn loose from the shafts m by the breaking of the screw pins or bolts p and p^2 , but if said 95 screw pins or bolts were to break, the worms n would be moved downwardly on the shaft m and the worms n^2 upwardly, and this movement of said gears would be limited by the sleeves o and o^2 , and the worms n and n^2 , and gears n^3 and n^4 and corresponding drums would be locked and the downward movement of the scaffold would be arrested, 100 as will be readily understood.

Our invention is not limited to any particular means for connecting the worms n and n^2 with the shafts m and any suitable construction may be provided for this purpose, and it will be understood that the gears h^2 , worms n and n^2 and the gears m^2 110 may be of any desired dimensions, and it will also be understood that the comparative dimensions of these gears control the speed of the drums g and h in the operation of raising and lowering the scaffold.

Our invention is not limited to the use of the grooved wheels or pulleys c^8 at the top of the main frame, and any suitable construction designed for the same, or a similar, use may be substituted therefor.

Having fully described our invention what we claim as new and desire to secure by Letters Patent is:—

An apparatus of the class described provided with a vertically arranged cable drum frame, cable drums mounted in said frame one above another and provided at one end with gears and at the opposite end with

ratchets, dogs connected with said frame and operating in connection with said ratchets, to prevent the backward movement of said drums, brackets connected with one side of 5 said frame, a crank shaft mounted in said brackets at right angles to the axis of said drums and provided with a worm, a shaft mounted vertically and at right angles to said crank shaft and provided with a gear 10 which meshes with the worm on the crank shaft, and worms connected with said ver-

tical shaft and meshing with the gears on said drum.

In testimony that we claim the foregoing as our invention we have signed our names 15 in presence of the subscribing witnesses this 12th day of April 1913.
